ALBERT SCHAUFELBERGER, OF PARIS, FRANCE.

CIRCULAR WEFT-WINDING MACHINE.

1,343,481.

Specification of Letters Patent. Patented June 15, 1920.

Application filed February 6, 1918. Serial No. 215,634.

To all whom it may concern:

Be it known that I, ALBERT SCHAUFELBERGER, a citizen of the French Republic, residing at No. 140 Boulevard Voltaire, Paris, France, have invented certain new and useful Improvements in Circular Weft-Winding Machines, of which the following is a specification.

The ordinary weft-winding machines as hitherto employed, wherein the weft is wound in intersecting spirals upon pirns, are machines wherein the spindles that carry the pirns are arranged in one or more straight rows, rotary motion being imparted 10 to the spindles from a common shaft with the necessary consequence that each spindle has to be provided with gear for throwing the driving mechanism into and out of engagement therewith. The winding of the 15 weft in intersecting spirals is effected by means of an oscillating weft guide which causes the weft to be wound upon the pirn in an up and down manner. The weft guide for each spindle thus necessitates a separate 20 drive for each cam.

The present invention has for its main object to provide an improved weft-winding machine of this type wherein the spindles are arranged circularly so that they can be 25 all driven together by a common wheel located inside the circle of the spindles, and all the weft guides are likewise driven by a common cam.

Another object of the invention is to provide improved mechanism for arresting the 30 motion of a winding pirn when the thread, being fed to that pirn, is broken.

A further object of the invention is to provide means for automatically stopping 35 the operation of a spindle, when the pirn on that spindle is completely wound.

A still further object of the invention is to furnish improved mechanism for insuring 40 tight winding of the pirns and for winding the pirns progressively from one end to 45 the other.

This invention will now be described with reference to the accompanying drawings which illustrate a circular weft-winding 50 machine with movable spindles. In these drawings:

Figure 1 is a section along the axis of the improved machine, and

Fig. 2 is a plan thereof.

55 Figs. 3, 4 and 5 which are drawn to an enlarged scale, are respectively a side eleva-

tion, a front elevation and a horizontal section on the line $a-a$ of Fig. 4, of a spindle with its accessories.

Figs. 6 and 7 illustrate a detail of the 60 means for effecting the automatic disconnection of a spindle.

Fig. 8 is a section of the cone mechanism for effecting the automatic descent of the 65 spindle during the winding of the weft.

In the ordinary machines of this type the weft is wound on a pirn consisting of an open tube of slightly conical shape with its smaller end uppermost, this tube generally 70 ends toward its base in a truncated conical portion, the angle of which is approximately that which it is desired to give to the upper portion of the body of the weft on the pirn during the winding. The pirn is mounted 75 on a rotary spindle. The weft is wound up and down upon the conical base. The weft 80 is guided to the pirn by a weft guide having vertical oscillatory movements of an amplitude equal to the height of said base. During the entire winding operation the upper 85 part of the body of the weft already wound on the pirn forms a cone having approximately the same angle as the base, while below the said cone the portion of the body of the weft which has already been completely wound, is cylindrical.

In addition to the above stated drawbacks of the straight-row weft-winding machines, there are to be added the very sudden 90 oscillations of the weft guide for effecting the winding of the weft in intersecting spirals; which oscillations subject the weft at each change of direction of motion to a sudden strain which is often the cause of the 95 breakage of the weft especially in the case of rough weft.

In contradistinction to the above, in circular weft-winding machines according to the present invention, the motion is extremely gentle in its action upon the crossing 100 of the weft, owing to the circumstance that the common rotary cam plate for operating the weft guide has long ascending and descending inclines.

A circular weft-winding machine with 105 movable spindles according to the present invention is illustrated in Figs. 1 to 8.

The framing of this improved machine consists (Figs. 1 and 2) of a bed-plate 1 carrying a lower plate 2 and an upper plate 3 connected together by uprights 4, 5, 6, 7. A vertical shaft 8 is mounted between these

two plates. This shaft 8 is fixed at its upper end to the cam plate 9 for the weft guide, which is a rotary plate formed with an edge the varying height of which imparts 5 to the weft the vertical oscillations that are necessary to produce the winding in intersecting spirals. The shaft 8 carries at its lower part a driving wheel 10 which produces the rotation of the spindles. This 10 mechanism comprising the shaft 8, the cam plate 9 and the driving wheel 10, is actuated by means of a leather-covered pulley 11 that drives the cam plate 9 from underneath. This pulley 11 is mounted on a shaft 12 15 which is fixed to the framing and along which latter it can move in such a manner as to vary the speed of driving. The shaft 12 is driven by a pulley 13. The spindle-driving wheel 10 meshes with pinions 14 mounted in sleeves 16 which constitute oil chambers and are fixed to the lower plate 2 by means of nuts 15 (Fig. 3). A driving sleeve 17 provided with a driving stud 18 engages with its cylindrical lower portion in the pinion 14. The driving stud 18 is adapted to drop into a semi-circular groove formed in the upper face of the pinion 14, so as to drive when it is in engagement. 19 is a round spindle extending inside the driving sleeve 17; this spindle is formed with a longitudinal groove 20 in which there engages an internal projection (not shown) of the sleeve 17. By this means the spindle 19 is permitted to move up and down in the sleeve 17 while being continuously rotated by the latter. The disengagement of the sleeve 17 and the pinion 14 is effected by means of the tappet 21 on the disengaging rod 22 which is adapted to raise or 30 permit lowering of the driving sleeve 17. The spindle 19 is guided at its upper part by a vertically movable support 23 (Figs. 3 and 5) through which the spindle passes freely and upon the upper end of which it rests with its base 24. Above the base the spindle 19 continues in the form of a straight stem upon which the pirn 25 is slipped. The movable support 23 is guided in a fixed support 27 fixed to the plate 3 45 and provided with two grooves 26 in which there freely engages a roller 29 mounted on a horizontal journal 28 (Fig. 4) carried by the movable support 23. This movable support 23 is balanced in the usual manner by means of a descending bar 30 to the end of which there is fixed a strap 32 which passing over the guide pulley 31, supports a counterweight 33. By this arrangement the 50 cop formed on the pirn is drawn upward. 55 In this movement, its conical portion encounters, when sufficient thickness of weft has become wound on, an inclined cone 34 (Fig. 4) that is mounted in a manner herein-after described. As best shown in Figs. 4, 60 7 and 8, the bearing cone 34 forces the spin-

dle and the pirn to descend. As best shown in Figs. 4, 7 and 8, the bearing cone 34 is rotatably mounted upon one arm of a bell-crank lever 59. This lever is fulcrumed upon a pin 61, which is adjustably mounted 70 in a curved slot 60 passing through an arm 27' fixed to the stationary guide 27. The lever carries a sleeve 59', which surrounds the pin 61 and a spring 62 is located in said sleeve and has one of its ends connected to 75 the sleeve and its other end fixed to the stationary washer 63 for the purpose of forcing the cone 34 toward the lower cone 25' of the pirn 25. It will thus be seen that the cone 34, by being resiliently forced toward 80 the pirn, has a tendency to cause the pirn to descend, as the thread accumulates upon the same. By this means the inclined portion of the weft cop is always located opposite the point where the weft executes 85 its vertical oscillations that are produced by the edge of varying heights of the weft guide cam 9. The fixed guide 27 carries a vertically extending post 36, which is bent downwardly and inwardly over the edge 37 90 of the cam plate 9. The inner end of the post 36 is bent into hook shape as shown at 52 and the free end of this hook-shaped part terminates in a substantially horizontal hook 35. The weft 35' coming from the 95 upper part of the machine (in the known manner) passes through the hook 35, over the edge 37 and is secured to the cone 25' of the pirn 25. It will be seen that as the pirns 25 are rotated the edge 37 of the rotating cam plate will first raise and then lower the thread 35', so that said thread will be spirally wound on the pirns. It will also be seen that the shape of the edge 37 will cause gradual upward and downward 100 movement of the thread and for this reason the thread will not be subjected to sudden movements, which would be liable to break the thread. The edge of the weft guide cam 9 is formed in such a 105 manner that its lowest point and its highest point shall correspond respectively to the bottom and to the top of the winding cone. But the profile of this edge has a shape suited to the winding which is desired to be 110 produced, and may have either a single incline as shown in the accompanying drawings, or it may have a plurality of ascending and descending inclines of suitable inclinations and lengths. The size of the cop is 115 regulated in the usual manner by moving the fulcrum 61 of the cone 34 (Fig. 4) along the slot 60, as this will cause the lower edge of said cone to be moved toward or away from the pirn, and consequently the thickness of 120 the cop may be decreased or increased. The spindle is thus compelled to descend only when the thickness of the weft, that is already wound on the inclined part, comes in contact with the cone 34. 125

The stop motion referred to heretofore serves to produce a stoppage of the rotation of the spindle when the weft breaks. This stop motion is constituted as follows: the 5 fixed support 27 (Fig. 6) carries a pin 38 on which is mounted the stop lever 39. This lever comprises two vertical limbs, namely, an upper limb 39^a a lower limb 39^b, and also a horizontal limb 39^c provided with a counterweight 46. The lower vertical limb has a stop shoulder 40 with which the tappet 41 of the vertically movable stop rod 22 is caused to engage by the action of the coiled spring 42 (Fig. 4). On the pin 38 there is 10 pivoted another vertical lever 43 which is downwardly directed and terminates at its lower part in an inclined arm. This lever 43 carries a tappet 44 against which the lower vertical limb 39^b of the lever 39 is caused 15 to bear by the action of the counterweight 46. The upper vertical limb 39^a of the stop lever 39 carries at its end a pin 47 on which is fulcrumed a lever 48 that is connected by a rod 49 to the weft stop motion device 51. 20 This stop motion device 51 is of angle shape and is pivoted on a pin 50 (Fig. 3) supported by the rod 36, the downwardly and inwardly extending end 51^a of the stop device 51 bears against the weft, coming 25 from above, before it enters the hook 35. If the weft should break, the stop motion device 51 will rock so that its end 51^a will move to the bottom of the hook-shaped part 52 and the inner end of the lever 48 30 (Fig. 6) will be permitted to drop by its own weight into alinement with the bottom 35 of the cam 9.

The bottom of the cam 9 is provided with a horizontally extending inclined plane 53 40 and when the inner end of the lever 48 falls into alinement with the bottom of the cam, said inner end will be engaged by this inclined plane 53 and this will cause the upper limb 39^a to move away from the vertical 45 axis of the machine and thus rock the stop lever 39. As the lever 39 rocks, its lower end releases the tappet 41 of the stop rod 22. When the tappet 41 is released, the coiled spring 42 (Fig. 4) will raise the rod 22 until 50 the tappet 41 contacts with the stop shoulder 45 (Fig. 6) of the lever 43. This rising movement of the stop rod 22 causes its lower tappet 21 to raise the driving sleeve 17, and consequently arrests the movement of the 55 spindle 19.

This stop motion mechanism is completed in such a manner that when the pirn has attained the desired length the spindle will be automatically stopped, and the spindle which 60 was in the lowest position rises automatically into the highest position; the supporting cone being moved away from it so as to allow of the removal of the filled pirn and of its replacement by an empty pirn. This mechanism is as follows: the movable support 23

of the spindle 19 (Fig. 6) is provided at its lower part with a tappet 54 which in moving down, strikes the inclined arm of the lever 43. This arm is capable of adjustment according to the length of the pirn. This 70 movement compels the lever 43 to rock toward the right and carry with it the lever 39 by means of the tappet 44. Consequently the stop shoulder 40 of the stop lever 39, and the stop shoulder 45 of the lever 43 are no 75 longer in the path of the tappet 41 of the stop rod 22. This rod is therefore caused by its spring to rise until its lower tappet 21 (Fig. 4) strikes against a lug 55 on its lower guiding support 56. This rise causes the 80 disengagement of the sleeve 17, and consequently the cessation of the rotation of the spindle. Further, the upper horizontal handle of the stop rod 22 strikes the tappet 57 (Fig. 4) which is fixed to the movable 85 abutment 58 that is guided in a socket of the fixed support 27 of the spindle. The abutment 58 raises the angle lever 59 carrying the cone 34, by causing it to rock on the pin 61. The cone 34 moves away from the 90 spindle 19 by an amount that is sufficient to allow free passage for the pirn which is caused by the counterweight 33 to return into its upper position. The attendant has now merely to remove the filled pirn and to re- 95 place it by an empty one. Then he presses upon the upper handle of the stop rod 22 which is sufficient to replace the handle and the cone 34 into operative position and to cause the spindle 19 to rotate. The cone 34 100 (Fig. 8) mounted on the angle lever 59, is returned into its operative position by the coiled spring 62.

What I claim is:—

1. In a weft-winding machine wherein the 105 weft is wound in intersecting spirals, the combination of spindles located along a circumference, a common wheel actuating said spindles, said spindles being movable along their axes and independent of one another; 110 cops having conical bases secured at the upper parts of the spindles, a circular plate having an edge of varying height serving as a common weft guide and rotating opposite the conical portion of the cops during the 115 winding, cones bearing on the cops, axes for said cones, springs tending to draw said cones downwardly, stop members for said cones, and adjusting slides in which the axes of the cones are engaged. 120

2. In a weft-winding machine wherein the weft is wound in intersecting spirals, the combination of spindles located along a circumference, a common wheel actuating said spindles, said spindles being movable along 125 their axes and independent of one another; cops having conical bases secured at the upper ends of the spindles; a circular plate having an edge of varying height and having an inclined plane at its outer part serv- 130

ing as a common weft guide and rotating opposite the conical portion of the cops during the winding, cones bearing on the cops, axes for said cones, springs tending to draw said cones downwardly, stop members for said cones, adjusting slides in which the axes of the cones are engaged, a device for stopping said spindles at a desired moment, and a weft

stop motion comprising a rocking tappet for operating the means for stopping the machine, operated by the inclined plane on the weft-guide plate. 10

In testimony whereof I have signed my name to this specification.

ALBERT SCHAUFELBERGER.
